UNITED STATES PATENT OFFICE.

FRANK G. STEINER, OF CHICAGO, ILLINOIS, ASSIGNOR TO STEINER SALES COMPANY,
OF SALT LAKE CITY, UTAH, A CORPORATION OF UTAH.

TOWEL CABINET.

Application filed October 3, 1927. Serial No. 223,696.

My invention relates to a towel cabinet wherein a web of towel is placed with provision for delivery of a clean portion thereof to the user, with means for winding up or withdrawing within the cabinet the soiled portion of the web as fast as the clean section is drawn out for use.

The object of my present invention is to improve a cabinet of this type shown and described in my application for Letters Patent of the United States, Serial Number 94,807, filed March 15th, 1926, and also the invention set forth in my pending application for Letters Patent of the United States Serial Number 167,256 filed February 10th, 1927.

A further object is to simplify and reduce the cost of manufacture of a cabinet of this type and perfect the means whereby the soiled towel can be easily and quickly removed when the clean supply is exhausted and the cabinet loaded or filled with a clean web and made ready for use.

A further object is to simplify and improve and make more positive the timing device or the means whereby the feed or delivery of the clean towel from the cabinet is controlled.

Other objects of the invention will appear from the following detailed description. The invention consists generally in various constructions and combinations all as herein described and particularly pointed out in the claims.

In the accompanying drawings forming part of this specification,

Figure 1 is a vertical sectional view through a towel cabinet embodying my invention;

Figure 2 is a similar view showing the pivoted or movable portion of the cabinet in its normal position in full lines and in its outwardly swung or loading position in dotted lines;

Figure 3 is a sectional view on the line 3-3 of Figure 2;

Figure 4 is a detailed sectional view showing the normal position of the parts of the timing mechanism when the cabinet is ready for use;

Figure 5 is a similar view showing the position assumed by the parts when the user has manipulated the time or control device and has begun the delivery of the towel;

Figure 6 is a sectional view on the line 6-6 of Figure 4;

Figure 7 is a sectional view on the line 7-7 of Figure 5;

Figure 8 is a front view of a portion of the cabinet showing the control mechanism and means for positively operating it through the movement of one of the rolls;

Figure 9 is a view taken on a line at right angles substantially to the view of Figure 8;

Figure 10 is a sectional view on the line 10-10 of Figure 9; and

Figure 11 is a sectional view on the line 11-11 of Figure 9.

In the drawings 2 represents the side walls of the cabinet; 3, the back thereof; 4, a top, 70 and 5 the door of the cabinet that is adapted to swing open to disclose the interior thereof. The bottom of the cabinet, except for a cross plate 6 is open, a passage 7 being provided between this plate and the front door 75 through which the clean web of towel depends and a gap 8 being provided between the plate 6 and the rear wall through which the soiled web is stretched upwardly to the winding roll within the cabinet. An inner 80 section for the cabinet forming the holder is provided comprising side plates 9 pivotally connected with the side walls of the cabinet at 10 so that this section or holder may swing outwardly on its pivots when the door 85 is open to the position indicated by dotted lines in Figure 2. Feed rolls 11 and 12 are mounted in the plates 9 preferably on the same level, one in front of the other, and having a driving connection 13 between 90 sprockets 14 for simultaneous synchronous movement of the rolls. The surfaces of these rolls are roughened by suitable means preferably by fastening sheets of sand paper thereto and one roll has a ratchet and pawl 95 device 15 which prevents backward movement of these rolls. A curved plate 16 is interposed between the plates 9 at the bottom and forms a support for a clean towel supply 17 which lies loosely on the plate and is 100

adapted to be turned thereon to unwind the web for the delivery of the clean section. From this supply the clean towel web is stretched upwardly into contact with the forward portion of the roll 11 and is then carried around what I prefer to designate as a pinch roll 18 that is mounted in slots 19 in the plates 9 and is adapted to rest by gravity upon the roll 11 and press the web of clean towel against the surface of the roll. The upper ends of the slots 19 are notched as at 20 so that in filling the cabinet the user can raise the pinch roll and let it rest in these notches during the operation of threading the towel over the pinch roll and around under the towel supply to the soiled towel winding roll. The rear portions of the plates 9 have slots 21 adapted to receive the winding roll 22, these slots being so arranged that the winding roll will contact with the feed roll 12 and the roughened surface of this feed roll contacting with the web of towel on the winding roll will, when the feed roll is revolved, revolve the winding roll also and wind up the soiled towel thereon. The web of clean towel after being carried down through the gap 7 is formed in a loop below the cabinet and the attendant having adjusted the pivoted section in the position indicated by dotted lines in Figure 2 will thread the loose end of the web up through the opening 8 to the winding roll and to insure tension on this web I prefer to provide a wall 23 over which the web slides and a projection 24 U-shaped substantially in cross-section and composed preferably of sheet metal and presenting a rounded surface for contact with the towel web, this projection being secured by suitable means such as the ears 25 to the side walls 2 on each side of the cabinet. Normally, the plates 9 forming the towel holder are locked within the cabinet by means of a spring stop device 26 having a pin 27 adapted to snap into holes 28 in one of the plates 9. In Figure 3 this is shown in position for locking the holder within the cabinet but when the pin 27 is pressed outwardly to disengage it from the outer hole, the holder may be swung forwardly on its pivots to the position indicated by dotted lines in Figure 2 when the pin 27 will snap into the rear hole 28 and lock the holder in its tilted loading position. The roll 11 is provided at one end with a head 29 and this head has an orifice 30 extending transversely of the roll. Within this orifice a bolt 31 is mounted and free to slide lengthwise within the orifice, being limited in its movement by a pin 32 mounted in the wall of the orifice and projecting into an annular groove 33 provided near the middle portion of the bolt. When the roll is in the position indicated in Figure 5, the bolt will drop by gravity so that one end will project beyond the peripheral surface of the roll and consequently when this projected end engages a fixed stop the feed mechanism will be locked until the bolt is released. Upon the release of the bolt and the subsequent revolution of the roll, the bolt will again slide by gravity and its end will be projected beyond the surface of the roll, when near the completion of the next revolution. A bracket 34 is secured to the wall of the holder and provided with a slot 35 and when the feed roll is completing its revolution the projecting end of the bolt will engage the wall 36 at the upper end of the slot and thereby further movement or revolution of the feed roll will be prevented. The bracket has a guideway 37 and a plate 38 is adapted to slide vertically in said guideway and the wall of the guideway opposite the slot 35 is provided with an opening 39 that is opened and closed alternately with the vertical movement of the slide 38. Below the slide, I provide a dashpot 40 adapted to contain a suitable noncompressible fluid such as oil. The dashpot has a head 41 at its upper end, a plunger 42, and a stem 43 that is connected at 44 to the slide 38. The plunger has a group of ports 45 extending therethrough around a central port 46 and a plate 47 is slidably mounted on pins 48 on the underside of the plunger and is adapted to close the ports 45 and has a port 49 to register with the port 46. This port 46 communicates with a transverse opening 50 in the stem of the plunger adjacent to the port 46 and a sleeve 51 has a threaded connection with the plunger rod 43 and is adapted to slide up and down on said rod and open or close the opening 50 and thereby permit or prevent the flow of the fluid therethrough on the downward stroke of the plunger. Thus the speed of descent of the plunger may be easily and quickly regulated. The head 29 is provided with a cam 52 secured thereto as shown in Figure 9 and this cam has a shoulder 53 adapted to engage a lug 54 which projects outwardly from the slide 38 so that when the feed roll is revolved the shoulder 53 will always engage the lug 54 and raise the slide to a point where it will close the opening 39 and prevent the operation of the locking bolt. The lug 54 is adapted to move vertically within a slot 55 and passes out of contact with the shoulder on the cam as it revolves and if preferred the dashpot device may be detached from this slide and when this is done the slide will drop by gravity to its lower position when the cam moves out of engagement with the lug 54 near the end of the revolution of the roll to be raised a second time to close the opening 39 upon the next revolution of the cam.

Various devices may be provided for releasing the locking bolt but I prefer to provide a bar 56 pivoted at 57 and having a

hooked pointed end 58 that is adapted to be projected through the opening 39 to engage and release the bolt 31. A flat spring 59 is mounted within a recess 60 in the inner face 5 of the door of the cabinet and a cap 61, cup-shaped substantially in form, is mounted on this spring and has its end projecting through an opening 62 in the door and forming a push button device by means of which 10 the bar 56 may be operated to disengage the locking bolt and allow the feed roll to be revolved.

The upper end of the slide 38 has a beveled surface 63 in position to contact with the beveled surface of the end 58 of the bar 56 and push the bar backwardly out of the opening 39 and allow the slide to move up between the pointed end 58 and the feed roll and effectually prevent a second or repeated 20 operation of the bar as shown clearly in Figure 5 of the drawing.

The slide when disconnected from the dashpot will be positively moved by the cam to a position in front of the bolt releasing 25 bar and will prevent operation of the bar during a portion of the revolution of the roll and if the bar should happen to be in its projected position when the slide is raised, the beveled surface of the slide engaging the 30 corresponding surface on the end of the bar will push it outwardly and the slide passing between the bar and the bolt will prevent inward movement of the bar until the slide is released upon the completion of a portion 35 of the revolution of the roll and cam. When the slide is connected to the plunger rod of the dashpot, the downward movement of the slide can be conveniently regulated so that several seconds may elapse after the completion 40 of revolution of the roll before the slide is allowed to move downwardly out of the path of the bolt operating bar. Thus the person in charge of the cabinet can, by the simple adjustment of the dashpot, regulate 45 the time of movement of the slide and discourage anyone maliciously or mischievously inclined from standing in front of the cabinet and operating the bolt releasing bar repeatedly and delivering more sections of 50 clean towel than he has need for or can conveniently use.

To hold the pinch roll in its operative position, I prefer to provide an arm 64 pivoted at 65 to the side wall of the holder and 55 normally adapted to overhang the axis of the pinch roll and prevent premature upward movement of the pinch roll while the cabinet is in use. Whenever desired, this arm may be swung to one side as indicated by dotted lines in Figure 2 and allow the 60 lifting of the pinch roll to its raised non-working position.

In loading the cabinet the holder will be 65 released by the movement of the locking devices 26 and 27 and swung out to the position

indicated by dotted lines in Figure 2 and locked in this position. The attendant may then place the supply of clean towel in the bottom of the holder. The end of the clean web will then be stretched upwardly into 70 contact with the feed roll 11 and over the pinch roll 18 and thence downwardly through the gap 7 to form a loop of suitable length below the cabinet. The end of the web is then passed upwardly through a gap 75 8 in the rear of the holder over the wall 23 and in contact with the projection 24, these devices having the function of smoothing 80 and straightening the wrinkles or folds in the web and applying a certain degree of tension thereto so that the web will be properly wound on the winding roll. The holder will then be swung back into the cabinet, the door closed and the cabinet is ready for use. The user approaching the cabinet will press 85 in the cap 61 and through the movement of the bar 56 disengage the locking bolt 31 so that pull upon the towel will revolve the feed rolls, deliver a predetermined length of 90 clean web and wind up a corresponding length of soiled web on the winding roll.

As will appear from the foregoing description the pinch roll, when the inner section of the cabinet is swung to its loading position, will be placed in the depressions or 95 notches 20 of the side plates, the arms 64 swinging to the dotted line position shown in Figure 2 to allow the pinch roll to be raised and seated in the depressions 20. When the towel has been properly stretched 100 within the cabinet with the clean loop depending below the casing as shown in Figure 1 the attendant will swing the inner section back to its normal position within the cabinet and then close the door of the cabinet, and 105 when the door is closed it will contact with the pinch roll and dislodge it from the depression 20 so that it will drop by gravity down upon the feed roll 11 beneath. In so doing the web of towel will be squeezed or 110 caught between the pinch roll and the feed roll 11 as shown plainly in Figure 1, and the arms 64 will swing back to their normal full line position over the journals of the pinch roll and prevent it from becoming prematurely raised until such time as the attendant 115 opens the door and swings the inner section of the cabinet forward to its loading position. Thus it is not necessary to rely on the memory of the attendant to put the pinch roll back to its normal or working position 120 as it will be automatically returned to such position when the attendant swings the inner section back into the cabinet and closes the door.

I claim as my invention:

1. In a towel cabinet, a roll to engage a web of towel, a locking bolt for normally holding said roll locked, a stop in the path of said bolt, a bar adapted to be operated 130

- by a user of the towel to engage and move said locking bolt to a release position, a cam operated from said roll, a member having a projection to engage said cam to move said 5 member into the path of said bar, said cam having means for holding said member in the path of said bar until said roll has completed a portion of its revolution.
2. In a towel cabinet, a roll to engage a 10 web of towel, a reciprocating locking bolt carried by said roll, a stop in the path of the projected end of said bolt, a bar mounted adjacent to said stop and adapted to be operated by a user of the towel to disengage 15 said bolt from said stop, a slide adapted to be moved to a position between said bolt and bar, means actuated by said roll to move said slide into the path of said bar, and prevent release of said bolt, said slide being 20 held by said means in such position during a portion of the revolution of said roll.
3. In a towel cabinet, a roll to engage a 25 web of towel, a locking bolt carried by said roll and having a movement transversely thereof, a stop in the path of the projected end of said bolt, a guide having an opening opposite said bolt, a slide movable in said 30 guide, a bar mounted adjacent to said guide and adapted to be operated by a user of the towel and projected through the opening in said guide to engage and move said bolt to its release position, means actuated by said 35 roll to move said slide into the path of said bar, said slide being held by said means in such position during a portion of the revolution of said roll.
4. In a towel cabinet, a roll to engage a 40 web of towel, a locking bolt carried by said roll for transverse movement therein, a stop mounted in the path of the projected end of 45 said bolt, a slide having a lug thereon, means mounted near said slide and adapted to be actuated by the towel user for moving said bolt to its release position, a cam operatively connected with said roll to engage said lug and move said slide into the path of said bolt moving means, said lug being adapted to ride on said cam and hold said slide in the 50 path of said bolt moving means until said roll has completed a portion of its revolution.
5. In a towel cabinet, a feed roll over 55 which a web of towel may be stretched for delivery to the user, a locking bolt carried by said roll and adapted to be projected outside the periphery thereof, a stop in the path of said bolt, a vertically movable slide having a beveled end, a bar mounted adjacent said slide and adapted to be operated 60 by the user of the towel to move said bolt to its release position, said bar having a beveled portion in the path of said slide whereby said bar will be forced outwardly when said slide is raised, and means connected with 65 said roll to engage and raise said slide into the path of said bar during the revolution of said roll, said means being adapted to hold said slide in its raised position until the roll completes a portion of its revolution.
6. In a towel cabinet, a feed roll for delivering a web of clean towel and a locking bolt carried by said roll and having a transverse movement therein, a stop adapted to engage the projected end of said bolt, a pivoted bar having means actuated by the towel user to 70 engage said bar with said bolt and move it to its release position, a slide, and a cam device associated with said roll and having means for moving said slide into the path of said bar when said bolt has been moved 75 to its release position, and a dash-pot having a plunger and rod connected with said slide and adapted to prevent its return to its normal position until a predetermined period has elapsed following the operation 80 of said slide moving means.
7. In a towel cabinet, a feed roll for delivering a web of clean towel, a locking bolt carried by said roll and having a reciprocating movement, a stop adapted to engage 85 the projected end of said bolt, a vertically arranged guide having an opening therein, a bar pivoted near said guide and having an end adapted to be projected through the opening in said guide by the towel user to 90 engage and move said bolt to its release position, a slide movable in said guide, means operated through the revolution of said roll to engage and raise said slide into the path of said bar, and a dash-pot having 95 a plunger and rod connected with said slide for holding it in its raised position for a predetermined period whereby a second operation of said bar and the release of said bolt is prevented until said period has 100 elapsed.
8. A towel cabinet comprising a casing, delivery and take up feed rolls mounted in said casing and having a driving connection between them, a door for the front of the 105 casing, said casing having slots in its side walls above said delivery feed roll, the upper ends of said slots having notches therein forming seats adjacent said door, a pinch roll adapted to move in said slots and over which 110 a web of clean towel may be stretched from a towel supply, said pinch roll being adapted when a pull is exerted on the towel web to press said web against the surface of said feed roll, the seats of said slots being adapted to receive said pinch roll when it is raised to a non-working position in filling the cabinet, and said door being adapted in closing to engage said pinch roll and dislodge it from said seats and allow 115 it to automatically drop to its working position.
9. A towel cabinet comprising a casing, a feed roll mounted in bearings in said casing, a pinch roll between which and said 120

feed roll a towel web may be stretched from a source of supply, and drawn over said pinch roll to depend therefrom, said casing having guides to receive said pinch roll, the 5 pull of the user on the towel web drawing said pinch roll downwardly in said guides against said feed roll, and a pivoted arm adapted to engage the spindle of said pinch roll and normally hold it in the lower portion of said guides.

In witness whereof, I have hereunto set my hand this 26th day of September, 1927.

FRANK G. STEINER.
